LENS ASSEMBLY FOR CONTINUOUSLY VARYING THE ANGULAR VIEW ON MOVIE CAMERAS

Eugene Martinez, Bronx, N. Y., assignor to The Ednalite
Optical Company, Inc., Peekskill, N. Y., a corpora-
tion of New York

Application September 30, 1955, Serial No. 38,183

Term of patent 14 years

(Cl. D61—1)

FIG. 1.

FIG. 2.

FIG. 3.

Fig. 1 is a top plan view of a lens assembly for continuously varying the angular view on movie cameras, showing my new design;

Fig. 2 is a rear elevational view; and

Fig. 3 is a front elevational view.

I claim:

The ornamental design for a lens assembly for continuously varying the angular view on movie cameras, substantially as shown.
